UNITED STATES PATENT OFFICE.

HARRY DANIEL LINDENMUTH, OF FLEMING, PENNSYLVANIA.

BUSHING-REMOVER.

1,342,852.

Specification of Letters Patent. Patented June 8, 1920.

Application filed July 19, 1919. Serial No. 312,039.

To all whom it may concern:

Be it known that I, HARRY D. LINDENMUTH, a citizen of the United States, residing at Fleming, in the county of Center 5 and State of Pennsylvania, have invented a new and useful Bushing-Remover, of which the following is a specification.

It is the object of this invention to provide a simple but efficient means whereby 10 bushings may be removed from a tubular element, and, in particular, to provide means whereby a bushing may be driven out of a tubular element.

It is within the province of the disclosure 15 to improve generally and to enhance the utility of devices of that type to which the invention appertains.

With the above and other objects in view, which will appear as the description proceeds, the invention resides in the combination and arrangement of parts and in the details of construction hereinafter described, it being understood that, within the scope of what is claimed, changes in the 25 precise embodiment of the invention shown can be made without departing from the spirit of the invention.

In the accompanying drawings:—

Figure 1 shows in longitudinal section, a 30 tubular element wherewith has been assembled a bushing remover embodying the invention, the remover appearing in elevation; Fig. 2 is a cross section on the line 2—2 of Fig. 1; and Fig. 3 is a side elevation of the bushing remover.

The numeral 1 denotes a tubular element. Bushings 2 and 3 are inserted into the ends 40 of the tubular element 1. The invention aims to provide a means whereby such parts as the bushings 2 and 3 may be removed readily from the tubular element 1.

In carrying out the invention there is provided an expansible U-shaped spring 4 including arms 5 provided at their free ends 45 with lateral projections 6. The projections 6 may be of any desired shape. They have been shown as being approximately semi-circular in top plan, but this detail is not insisted upon. It is necessary, merely, that 50 the projections 6 be small enough so that when the arms 5 of the spring 4 are pressed together, the projections may be inserted

through the bore of one of the bushings, for instance, the bushing 3.

The invention comprises, further, a 55 punch, denoted generally by the numeral 7, and including a body having a reduced extension 9 defining shoulders 10.

In practical operation, the arms of the spring 4 are pressed together, and the free 60 ends of the arms 5, carrying the projections 6, are inserted through the bushing which is to be removed. The arms 5 then are released, whereupon they will expand, so that the projections 6 overlap the inner end of 65 the bushing 3. The punch 7 is then inserted through the bushing 2, the extension 9 of the punch entering between the arms 5 and the shoulders 10 engaging the extremities of the arms 5, the projections 6, 70 or both of these elements. It is obvious that when the punch 7 is driven forwardly by a hammer blow, the spring 4 and its projections 6 will be advanced, the bushing 3 thus being driven out of the tubular element 1. 75 The extension 9 of the punch 7, being located between the free ends of the arms 5 of the spring 4, prevents the arms 5 and the projections 6 from springing toward each other, should the inner end of the bushing 3 be slightly beveled, battered, or otherwise misshapen, so as not to present a square end for engagement by the projections 6. Since the spring 4 is expansible, the device, in a single form, may be used 80 readily on bushings having different internal diameters.

Having thus described my invention, what is claimed is:—

A bushing remover comprising a U- 90 shaped spring provided with outwardly extended projections; and a punch including a body having a reduced extension defining a shoulder, the extension being received within the spring, and the shoulder engaging one end of the spring.

In testimony that I claim the foregoing as my own, I have hereto affixed my signature in the presence of two witnesses.

HARRY DANIEL LINDENMUTH.
